(73) Assignee: **WHIRLPOOL CORPORATION**,
Benton Harbor, MI (US)

(**) Term: **15 Years**

(21) Appl. No.: **29/813,549**

(22) Filed: **Oct. 29, 2021**

Related U.S. Application Data

(63) Continuation of application No. 29/732,296, filed on
Apr. 23, 2020, now Pat. No. Des. 939,272, which is
a continuation of application No. 14/983,735, filed on
Dec. 30, 2015, now Pat. No. 10,820,735.

(57)

CLAIM

The ornamental design for a food processing attachment, as shown and described.

DESCRIPTION

FIG. 1 is a front-right perspective view of a food processing attachment according to the design; and,

FIG. 2 is a back-right perspective view thereof.

The portions of the article shown in even broken line form no part of the claimed design.
